UNITED STATES PATENT OFFICE.

VERNON ROYLE, OF PATERSON, NEW JERSEY.

ROUTING MACHINE.

Application filed January 11, 1923. Serial No. 612,139.

This invention relates to an improvement in routing machines, and has for an object to provide a guide bar for the cutter arm which is very durable and wear resisting, the wear receiving portion of which may be readily adjusted to successively present new surfaces to the cutter arm as perceptible wear eventually takes place, and the said portion of which may also be very easily removed and replaced with a new portion without the necessity of disconnecting any substantial parts or removing the main body portion of the guide bar.

Another object consists in providing a device which serves as a combined stop and holder for limiting the movement of the cutter arm away from the work and for holding said arm in inoperative but readily accessible position.

Another object consists in providing certain improvements in the form, construction and arrangement of the several parts, whereby the above named and other objects may be effectively attained.

Practical embodiments of the invention are shown in the accompanying drawings, in which

Fig. 1 represents a top plan view of a portion of a routing machine with my improvements applied thereto.

Fig. 2 represents a detail elevation, on a large scale, showing my improvements and their immediate supporting members.

Fig. 3 represents an end elevation of the parts shown in Fig. 2.

Fig. 4 represents a vertical section taken in the plane of the line IV—IV of Fig. 2, looking in the direction of the arrows, with the stop and holding device removed.

Fig. 5 represents a similar view taken in the plane of the line V—V of Fig. 2, looking in the direction of the arrows.

Fig. 6 represents a front elevation of the stop and holding device, several positions of the cutter arm being shown in dotted lines.

Fig. 7 represents an edge view of the said device.

Fig. 8 represents a perspective view of a modified form of stop and holding device, several positions of the cutter arm being shown in dotted lines.

In view of the fact that the routing machine itself constitutes no part of this invention and that the same is applicable to many, if not all, approved forms of said

machines, the same will not be described in detail, but it will be noted that the machine in general is represented by 1 and that it has the usual cutter arm 2, which is pivoted at 3 and carries a cutting tool 4 that is suitably driven by belting 5 for operation upon the work 6. The front portion of the machine is provided with a pair of supporting members 7, that also act as guides for lifters 8, 9, the upper ends of which are intended to carry the guide bar which serves as a rest for the cutter arm 2 as it is swung laterally by the operator during the functioning of the machine, the lifters 8, 9 being commonly operable by a treadle connected therewith by suitable mechanism for the purpose of elevating the cutting tool 4 away from the work 6. This mechanism is all thoroughly understood by those acquainted with this art so that it is not necessary here to more fully show or describe the same.

The guide bars which have heretofore commonly been employed have been made of wood, and there has been an objectionable feature in that the frictional engagement of the cutter arm with the guide bar comparatively quickly wears away portions of the wood so that it no longer presents a level surface parallel with the work, and thereby becomes unsuited to the accurate performance of its function as a guide bar for the cutter arm. This has necessitated frequent removal of the guide bar and replanning of the same in order to level off its operative surface.

As is also well known in the art, the operator frequently desires to move the cutter arm to one side away from the work so that he can perform certain manual operations, or for other reasons; and it is also well known that the operator frequently desires to have the cutter arm held in such out of the way position until he manually brings it back into operative position. To this end, it has been customary to provide the cutter arms with a coil spring connected to some part of the framing of the machine or to any other convenient point, whereby the arm will be yieldingly held at one side of the machine and elevated from the level of the work. When the machine is thus equipped, it is necessary for the operator to move the cutter arm manually back into operative position and hold it there against tension of the spring while the cutting tool is in contact with the work. Furthermore, if the

spring is not connected at an entirely suitable point or when it becomes stretched or weakened with usage, it is common for the cutter arm to swing back and inconvenience the operator at times when he desires it to be held clearly away from him and the work.

My invention contemplates improvements overcomes the objections hereinabove mentioned, as well as others inherent in the previous arrangements employed.

Referring to the guide bar structure, clearly shown in Figs. 2 to 5 inclusive, it will be observed that the lifter 8 has a head 10 secured to its upper end by a pin 11, while the lifter 9 has a hub 12 which embraces its upper end, and into the top of which the said lifter is riveted, as clearly shown at 13 in Fig. 4.

20 My improved guide bar consists of a main body portion 14, composed of suitable metal, which is secured to the head 10 and hub 12 by cap screws 15, 16 which fit loosely in apertures 17, 18 formed in the body portion 14. This loose fit enables the guide bar to be adjusted to a perfect level by screws 19, 20 that are threaded into the head 10 and hub 12 respectively and bear against lugs 21, 22 formed at the lower portion of the 30 body member 14.

The upper portion of the body member 14 has a longitudinal slit 23 which is developed at its upper end into curved form in order to constitute a seat for a rod 24 composed of steel or other suitable wear resisting metal. The seat is sufficiently deep so that the rod 24 is slightly more than half embedded therein, and a series of screws 25 are arranged so as to clamp the upper edges 35 of the body portion 14 toward each other and thereby firmly grip the rod 24 in its seat, as clearly shown in Figs. 4 and 5. As the material of the walls of the longitudinal slit 23 is relatively thin there is naturally a 40 certain yielding flexibility so that they may be moved toward and away from each other by the screws 25 to accommodate rods of various diameters. The end of the rod 24 has a kerf 26, as shown in Fig. 3, and it 45 will be seen that by slightly loosening the screws 25, the rod may be turned with the aid of a screw driver so as to present different portions of its surface on the top of the guide bar. A further loosening of the 50 screws 25 will permit the complete removal of the rod 24 and its replacement by a new one.

As a result of this construction, the guide bar is composed of wear resisting material, 60 its operative surface member, when worn, may be quickly turned so as to present a perfectly level surface without the removal of any part or the necessity of any such operation as planing, and its surface member 65 may be bodily removed and replaced by a

new one without disconnecting the main body portion of the guide bar from the machine.

At one end of the guide bar is secured the combined stop and holding device for 70 the cutter arm, which is denoted by 27 and is fixed in place by a bolt 28. This device has a hook-like shape with one end offset from the plane of the remainder so as to resemble an incomplete spiral turn. Its upper extremity or prong is curved downwardly so as to be adapted to partially embrace the cutter arm, as indicated at 29, Fig. 6, and prevent it from upward or lateral movement under the influence of the usual spring; while its lower extremity or prong is curved slightly upwardly in order to form a seat to prevent lateral or downward movement of the cutter arm, represented at 30, Fig. 6, 80 which is not provided with the customary spring. The device itself, by reason of its location at the end of the guide bar, constitutes a stop which prevents further horizontal swinging movement of the cutter arm, as shown at 31, Fig. 6, after the latter has 90 come into contact therewith. In the position marked 31, the arm is supposed to be resting upon the guide bar and the tool to be at the level of the work.

The offsetting of the upper extremity or 95 prong of the device from the plane of the lower extremity or prong, as hereinabove mentioned, facilitates the entrance of the cutter arm into engagement with the device, as indicated in positions 29 and 30, Fig. 6.

In Fig. 8, I have shown a modified form of the combined stop and holding device. This device, which is represented by 32, is intended to be secured to the guide bar in the same manner as the preferred form. Its 105 shape, however, is somewhat different from that of the preferred form and it is preferably composed of sheet metal. This form is designed to cooperate with the end of the cutter arm in four positions of the latter; the one marked 33 indicating the position in which the arm may be held against upward and lateral movement when it is provided with the customary spring; the ones marked 34 and 35 indicating the positions 110 in which the arm may be held against downward and lateral movement when it is not provided with the usual spring; and the one marked 36 denoting the position of the cutter arm when it abuts the device as a stop. In the positions 33, 34 and 35, the arm is held elevated to such an extent that the cutting tool is above the level of the work, while in the position marked 36, the arm is supposed to be resting upon the guide bar 120 and the tool to be at the level of the work.

It will be understood that various changes may be resorted to in the form, construction and arrangement of the several parts without departing from the spirit and scope of 130

the invention; hence, I do not intend to be limited to the details herein shown and described except as they are included in the claims.

5. What I claim is:

1. In apparatus of the character described, a guide bar having a metallic wearing surface throughout its length and means supporting said bar to allow its rotation to 10 present different bearing surfaces for the support of a sliding tool arm.

2. In apparatus of the character described, a guide bar having a longitudinal slit therein to form yielding walls, and a 15 wearing surface supported throughout its length in said slit between said walls.

3. In apparatus of the character described, a guide bar having a longitudinal slit therein to form yielding walls, and a 20 metallic wearing surface supported throughout its length in said slit between said walls.

4. In apparatus of the character described, a guide bar having a longitudinal slit therein to form yielding walls, a wearing 25 surface supported throughout its length in said slit between said walls, and means for removably clamping the wearing surface in the slit.

5. In apparatus of the character described, a guide bar having a longitudinal slit formed therein, the opening of said slit being curved in cross section, and a substantially round metallic wearing surface supported throughout its length in said curved 35 portion of the slit to permit rotation of the said wearing surface.

6. In apparatus of the character described, a guide bar having a longitudinal slit formed therein, the opening of said 40 slit being curved in cross section, and a substantially round metallic wearing surface supported throughout its length in said curved portion of the slit, whereby said wearing surface may be adjusted in a rotary 45 direction to present different portions of its surface for contact with the cutter arm of the said apparatus.

7. In apparatus of the character described, a guide bar having a slit formed 50 therein, the opening of said slit being curved in cross section, and a substantially round wearing surface supported throughout its length in said curved portion of the slit, the end of said wearing surface being 55 provided with a kerf for adjusting it in a rotary direction to present different portions of its surface for contact with the cutter arm of the said apparatus.

8. In apparatus of the character de-

scribed, a guide bar, and a combined stop 60 and holder mounted on one end of said guide bar for limiting the lateral movement of the cutter arm of the apparatus while substantially in contact with the guide bar, and also for holding the cutter arm in an 65 inoperative position with respect to the guide bar.

9. In apparatus of the character described, a guide bar, and a device mounted on one end of said guide bar for holding 70 the cutter arm of the apparatus in an inoperative position with respect to the guide bar.

10. In apparatus of the character described, a guide bar, and a device mounted 75 on one end of said guide bar for holding the cutter arm of the apparatus in an inoperative position with respect to the guide bar and against upward movement.

11. In apparatus of the character described, a guide bar, and a device mounted on one end of said guide bar for holding the cutter arm of the apparatus in an inoperative 80 position with respect to the guide bar and against downward movement.

12. In apparatus of the character described, a guide bar, and a device mounted on one end of said guide bar for holding the cutter arm of the apparatus in an inoperative position and against lateral movement. 85

13. In apparatus of the character described, a guide bar, and a device mounted on one end of said guide bar for holding the cutter arm of the apparatus in an inoperative position with respect to the guide bar and against upward and downward movement. 95

14. In apparatus of the character described, a guide bar, and a device mounted 100 on one end of said guide bar for holding the cutter arm of the apparatus in an inoperative position with respect to the guide bar, and against upward, downward and lateral movement. 105

15. In apparatus of the character described, a guide bar, and a device mounted on one end of said guide bar for holding the cutter arm of the apparatus in an inoperative position with respect to the guide bar, 110 said device consisting of a two pronged hook having one prong offset from the plane of the other.

In testimony, that I claim the foregoing as my invention, I have signed my name 115 this fifth day of January, 1923.

VERNON ROYLE.
